UNITED STATES PATENT OFFICE.

RICHARD H. DAVIS, OF SYRACUSE, NEW YORK, ASSIGNOR TO CHRISTOPHER C. BRADLEY, OF SAME PLACE.

VEHICLE-SPRING ATTACHMENT.

SPECIFICATION forming part of Letters Patent No. 390,573, dated October 2, 1888.

Application filed July 20, 1888. Serial No. 280,525. (No model.)

To all whom it may concern:

Be it known that I, RICHARD H. DAVIS, of Syracuse, in the county of Onondaga and State of New York, have invented new and useful 5 Improvements in Axle-Connections for Vehicles, of which the following is a specification.

This invention relates to that class of vehicles in which the ends of the springs which support the body are attached to the axles.

10 In one construction the axles are bent or constructed with a depressed body and the springs are connected by shackles or loops with the ears at the inner ends of the axle-shanks. These shackles have heretofore been attached 15 to the axle by bolts passing through holes in the axle, but this construction is objectionable, as the connection becomes loose in course of time, causing it to rattle.

20 The object of my invention is to remedy this defect; and it consists of the improvements which will be hereinafter fully described, and pointed out in the claims.

25 In the accompanying drawings, Figure 1 is an elevation of an axle and connecting parts provided with my improvement. Fig. 2 is a fragmentary elevation of one of the end portions of the axle, the supporting-spring, and the shackle on an enlarged scale. Fig. 3 is a vertical longitudinal section of said parts.

30 Fig. 4 is a top plan view of the same parts. Fig. 5 is a cross-section in line $\alpha\alpha$, Fig. 3, looking in the direction of the arrow. Fig. 6 is a top plan view showing a slightly-modified construction of the shackle.

35 Like letters of reference refer to like parts in the several figures.

A represents the depressed body of the axle, and $a a$ are the raised shanks thereof, which carry the arms or spindles upon which the 40 wheels are mounted.

B represents the semi-elliptical spring supporting the body of the vehicle and attached with its ends to the shanks a of the axle by loops or shackles C.

45 Each shank a is provided on its upper side near its inner end with a transverse recess or depression, d , in which the adjacent cross-bar c of the loop C is seated, as clearly represented in Fig. 3.

e represents a clamping-plate secured to 50 the upper side of the shank a and bearing with its free inner end upon the cross-bar c of the loop, so as to hold the same in its seat. The clamping-plate e is secured to the shank a by a clip, f , surrounding the shank a , and a yielding filling-piece or cushion, g , preferably of wood, interposed between the upper side of the clamping-plate and the bow or upper curved portion of the clip, as shown in Figs. 2 and 3. 55

The clamping-plates e may be made of steel or iron and are preferably constructed of untempered steel. h represents depending lips or ears formed on opposite sides of the clamping-plates e and bearing against opposite sides 60 of the shanks a , so as to hold the clamping-plates against lateral displacement on the shank. 65

The clamping-plates e hold the cross-bars of the shackles C in frictional contact with their 70 seats at all times, and thus prevent rattling of the shackles, and they are sufficiently elastic to allow the cross-bars to turn in their seats, and permit the shackles to adapt themselves to the movements of the supporting-spring B. 75

When the contact-surfaces of the loop and its seat become worn or loose, the play is readily taken up by tightening the clip.

80 The loops or shackles C may be formed in one piece and the end of the spring be bent around the adjacent end bar of the loop, as represented in Figs. 2, 3, and 4, or one of the end bars of the loop may consist of a removable bolt which passes through openings in the side bars of the loop and through an eye 85 formed at the end of the spring, as represented in Fig. 6.

I claim as my invention—

1. The combination, with an axle provided with a recess or seat, of a shackle arranged in 90 said recess or seat and a clamping-plate attached to the axle and bearing upon said shackle, substantially as set forth.

2. The combination, with the axle provided with a recess or seat, of a shackle or loop 95 seated in said recess or seat, a clamping-plate bearing upon said shackle or loop, a clip whereby the clamping-plate is secured to the

axle, and a cushion interposed between the clip and the clamping-plate, substantially as set forth.

3. The combination, with the axle provided
5 with a recess or seat, of a shackle or loop seated in said recess or seat and a clamping-plate bearing upon the shackle and provided at its ends with lips bearing against the sides of the axle, substantially as set forth.

Witness my hand this 16th day of July, 10
1888.

RICHARD H. DAVIS.
